FASTENING INSERTING MACHINE

Fred L. MacKenzie, deceased, late of Beverly, Mass., by Effie L. MacKenzie, administratrix, Beverly, Mass., assignor to United Shoe Machinery Corporation, Paterson, N. J., a corporation of New Jersey

Application March 7, 1935, Serial No. 9,845

8 Claims. (Cl. 1—20)

This invention relates to improvements in fastening forming and inserting machines and is illustrated herein as embodied in a machine particularly adapted to form and insert staples.

5 In some commercial types of staple forming and inserting machines staples are formed from lengths of wire having beveled ends, the cut ends of the legs of each staple being inclined in opposite directions. When a staple of this type 10 is inserted in a work piece one leg of the staple is deflected in one direction and the other leg is deflected in the other direction. Such staples form effective fastenings but under some conditions, for example, when staples are inserted close 15 to the edge of a work piece, one of the staple legs may be deflected outwardly through the side of the work piece thus damaging the work and seriously impairing its appearance.

An object of the present invention is to provide an improved machine for forming and inserting staples by the use of which the above-mentioned difficulties will be overcome. To this end the machine is provided with a staple forming mechanism which is arranged to shape the point 20 of one leg of a staple after the staple has been formed. As illustrated, the inside former of the machine is provided with an abutment having an inclined surface. A staple having a short leg and a long leg is formed about the inside former, the legs of said staple having oppositely inclined ends. After the staple has been formed, the inside former is moved to bring the inclined surface of the abutment into engagement with the short leg of the staple to shape said leg in a 25 manner which will overcome its tendency to deflect when driven.

With the above and other objects and features in view the invention will now be described with reference to the accompanying drawing and 30 pointed out in the claims.

In the drawing,

Fig. 1 is a view, in side elevation, partly in section, of a portion of a machine illustrating a preferred embodiment of the present invention;

Fig. 2 is a detail view, in section, on an enlarged scale of the staple forming mechanism of the machine;

Fig. 3 is a detail view, in section, of the yielding connection between the inside former and its operating cam; and

Fig. 4 is a view on an enlarged scale of a staple formed on the illustrated machine.

The present invention is illustrated as embodied in a machine of the type disclosed in United States Letters Patent No. 1,016,930,

granted February 13, 1912, on an application filed in the name of William H. Borden, to which reference may be had for a description of those parts of the machine which it is not necessary to describe herein.

The illustrated machine is provided with a head 10 in which the operating instrumentalities of the machine are mounted. An operating shaft 12 is journaled in suitable bearings in the head 10. A cam 14 is secured to the shaft 12 and is provided with a closed cam track 16 which operates an inside former 18 through connections which will now be described. A cam roll 20 (shown in dotted lines in Fig. 1) connected to a horizontal slide 22 enters the cam track 16. The slide 22 is 15 mounted on a rock shaft 24, one end of which is journaled in a bearing 26 formed in the head 10. The other end of the shaft 24 is journaled in a bearing (not shown) at the front of the head 10. The slide 22 is provided with a downwardly extending arm 28 which at its lower end is pivotally secured to a member 30. A bushing 32 is secured in the member 30 by a clamping screw 34. The bushing 30 is provided with internal screw threads at one end and receives a locking 25 nut 36 which is arranged to bear against one end of a stiff spring 38. The other end of the spring bears against a washer 40 surrounding the reduced end of a rod 42. The washer 40 bears against a shoulder formed at the juncture of the 30 reduced portion of the rod 32 and the tension of the spring 38 is adjusted by means of an adjusting nut 44 threaded to the reduced end of the rod 42. The adjusting nut 44 is locked to the reduced end of the rod 42 by a clamping screw 46. When it is necessary to adjust the tension of the spring 38, the clamping screw 46 is loosened and the adjusting nut 44 is turned until the desired tension is applied to the spring 38. The adjusting screw is 35 then locked by tightening the clamping screw 46. The spring 38 forms a yieldable connection between the arm 28 and the rod 42 for purposes which will later be described.

The rod 42 is mounted for sliding movement in a suitable bearing formed in the head 10 of the machine. The inside former 18 is secured to the forward end of the rod 42 by screws 48 and is provided with a projecting abutment member 50, as shown in Figs. 1 and 2. The forward end of the member 50 is provided with a 50 surface 52 which is inclined toward the front of the machine. In Fig. 1, the inside former 18 is shown in the position which is occupied during the staple forming operation. It is to be noted that when the former 18 is in this position the 55

forward end of the member 50 is so located that it does not interfere with the staple forming operation. The inclined surface 52 is located just behind a staple 54 when the staple is formed.

5 After the staple 54, which is provided with a long leg 56 and a short leg 58 (Fig. 4), has been formed, the inside former 18 is moved forwardly and the inclined surface 52 on the member 50 engages the point of the short leg 58 and bends 10 the point of the short leg to an extent which renders it substantially symmetrical with respect to the center line of the short leg 58. After the point of the short leg 58 has been shaped as described above, the inside former 18 is moved 15 rearwardly by the action of the cam track 16 in the cam member 14 out of the path of movement of a driver 70.

When a staple or other fastening having a beveled point is driven into a work piece, the 20 fastening is deflected in the direction of the bevel. The long leg 56 of the staple 54 is so located relatively to the edge of the work that the leg 56 is deflected away from the edge of the work but the short leg 58 is deflected slightly 25 in the opposite direction toward the edge of the work. The leg 58 is relatively short and, consequently, under ordinary conditions, if not shaped as just described, the deflection would be slight but in some cases where the staple 30 is inserted close to the edge of the work the leg 58 might be deflected sufficiently to penetrate through the edge of the work. This, however, will not occur if the leg of the staple is shaped by the mechanism of my invention.

35 The yieldable connection, above referred to, which includes the spring 38, is provided to prevent breakage of the connections between the inside former 18 and the cam track 16. The tension of the spring 38 is so adjusted that the 40 spring will yield if the former 18 meets an obstruction in the staple forming passage but is great enough to prevent yielding of the spring 38 when the point of the short leg 58 of the staple is being deflected.

45 The illustrated machine is provided with wire feeding and severing mechanism of the type disclosed in the Letters Patent above referred to. After the inside former 18 has been moved into the position shown in Fig. 1 and the wire has 50 been fed and severed, an outside former 62 is moved downwardly to the position shown in Fig. 1 to form a staple about the inside former 18. The outside former 62 is operated by connections to a cam track (not shown) in a cam 55 member 64. These connections include an arm 66 which is fixed to the forward end of the rock shaft 24, as disclosed in the above-mentioned Letters Patent. The other end of the rock shaft 24 has fixed thereto an arm 68 which carries a 60 cam roll entering the cam track in the cam 64. After the staple 54 has been formed the inside former 18 moves forwardly to engage the point of the short leg 58 with the inclined surface on the abutment member 50 to deflect the point as 65 hereinbefore described. The inside former 18 is then returned to its initial position and then a driver 70 is moved downwardly by a spring (not shown) to drive the finished staple 54 through a driver passage in a stationary throat 72 and into a work piece mounted on a work support 74.

70 The illustrated construction is particularly adapted for use in securing top lifts to heels in the manner disclosed and claimed in an application for United States Letters Patent Serial No. 75 3,956, filed January 29, 1935, in the name of

John W. Counter. It is to be understood, however, that the illustrated machine is not limited in its utility to use in such work since it may advantageously be used to secure together parts of other types of work pieces.

5

Having thus described the invention, what is claimed as new and desired to secure by Letters Patent of the United States is:

1. In a staple forming and inserting machine, an inside former, an outside former arranged for movement to form a staple about said inside former, and means constructed and arranged to move said inside former into the path of movement of the outside former prior to the staple forming operation and also further to move the 15 inside former to deflect the point of one of the staple legs after the staple has been formed.

2. In a staple forming and inserting machine, an inside former, an outside former arranged for movement to form a staple about said inside former from a length of wire having beveled 20 ends, and means constructed and arranged to move said inside former into the path of movement of the outside former prior to the staple forming operation and also further to move the 25 inside former to deflect one of the beveled ends of the staple after the staple has been formed.

3. In a staple forming and inserting machine, an inside former having a projection thereon, an outside former arranged for movement to form 30 a staple about said inside former, and means constructed and arranged to move said inside former into the path of movement of the outside former prior to the staple forming operation and further to move the inside former to cause the projection 35 thereon to engage and shape the point of one of the staple legs after the staple has been formed.

4. In a staple forming and inserting machine, an inside former having a projection thereon, an outside former arranged for movement to form 40 a staple about said inside former from a length of wire having beveled ends, and means constructed and arranged to move said inside former into the path of movement of the outside former prior to staple forming operations and also to move the 45 projection on said inside former into engagement with one of the beveled ends of the staple to deflect said end after the staple has been formed.

5. In a staple forming and inserting machine, an inside former, an abutment on said inside 50 former having an inclined surface, an outside former arranged for movement to form a staple about said inside former, and means constructed and arranged to move said inside former into the path of movement of the outside former prior 55 to the staple forming operation and also to move the inclined surface of said abutment against the point of one of the staple legs to shape said leg after the staple has been formed.

6. In a staple forming and inserting machine, 60 an inside former, an inclined abutment carried by said inside former, an outside former arranged for movement to form about said inside former a staple having a short leg and a long leg, and means for moving said inside former into the 65 path of movement of said outside former prior to the staple forming operation and also to move the inside former to cause the inclined abutment to engage the short leg of the staple to shape said leg after the staple has been formed.

70

7. In a staple forming and inserting machine, an inside former, an inclined abutment carried by said inside former, an outside former arranged for movement to form about said inside former a staple having a short leg and a long leg, said 75

5 legs having oppositely inclined ends, and means for moving the inside former into the path of movement of the outside former prior to the staple forming operation and also to move the inclined abutment into engagement with the short leg of the staple to shape the point of said leg after the staple has been formed.

8. In a staple forming and inserting machine, an inside former, an abutment carried by said 10 inside former having an inclined surface, an outside former arranged for movement to form about said inside former a staple having a short leg and a long leg, said legs having oppositely inclined ends, means for moving the inside former

into the path of movement of the outside former prior to the staple forming operation and also to move the inclined surface of the abutment into engagement with the short leg of the staple to shape the point of said leg after the staple has been formed, and a connection between said inside former and said means for moving the inside former arranged to yield when the inside former meets an excessive resistance in its movement toward staple forming position.
